Specification for Design.

Patented Oct. 7, 1919.

Application filed June 20, 1919. Serial No. 305,667. Term of patent 14 years.

To all whom it may concern:

Be it known that I, CAP B. COLLINS, a citizen of the United States, residing in Oak Park, in the county of Cook and State of Illinois, have invented a certain new, original, and ornamental Design for Razors, of which the following is a specification, reference being had to the accompanying drawing, forming part thereof.

The figures of the drawing are as follows:

Figure 1 is a perspective view of the razor looking from underneath; and

Fig. 2 is another perspective view looking somewhat downwardly.

I claim:

The original design for a razor as shown.
